COMBINED TOWEL DISPENSER AND WASTE RECEPTACLE

Joseph C. Grasso, New York, and Patrick Grasso, Scarsdale, N.Y., assignors to Accessory Specialties, Inc., Long Island City, N.Y., a corporation of New York

Filed Dec. 23, 1965, Ser. No. 310

Term of patent 14 years

(Cl. D4—3)

Fig. 1

Fig. 3

Fig. 2

FIG. 1 is a perspective elevational view of a combined towel dispenser and waste receptacle embodying our new design;

FIG. 2 is a bottom perspective view thereof;

FIG. 3 is an elevational view thereof, all four elevational views being identical; and

FIG. 4 is a top plan view thereof.

We claim:

The ornamental design for a combined towel dispenser and waste receptacle, as shown and described.
